UNITED STATES PATENT OFFICE.

HERMANN THUN, OF ESSEN-ON-THE-RUHR, GERMANY, ASSIGNOR TO FRIED. KRUPP AKTIENGESELLSCHAFT, OF ESSEN-ON-THE-RUHR, GERMANY.

AUTOMATIC STAMP-DELIVERY MACHINE.

1,427,136.

Specification of Letters Patent. Patented Aug. 29, 1922.

Application filed December 6, 1920. Serial No. 428,800.

To all whom it may concern:

Be it known that I, HERMANN THUN, residing at Essen-on-the-Ruhr, Germany, a citizen of the German Republic, have invented a certain new and useful Improvement 5 in Automatic Stamp-Delivery Machines (for which I have filed an application in Germany July 1, 1919), of which the following is a specification.

10 The subject matter of the invention is an automatic stamp delivery machine which is capable as required, either of delivering an unmoistened stamp or providing a thing to be posted with a stamp.

15 On the drawing an example of construction of the subject matter of the invention is shown. On this drawing:

Fig. 1 is a longitudinal section of the device, some parts being omitted,

20 Fig. 2 is the same section as Fig. 1 with a different position of the individual parts,

Fig. 3 a plan view on a larger scale of a part of the device,

Fig. 4 is a part of Fig. 1 on a larger 25 scale,

Fig. 5 is a side view of Fig. 4, partly in section and with certain parts omitted, and

Fig. 6 is a part of Fig. 4 with certain elements in different positions.

30 In a casing A a shaft B is mounted which can only be turned clockwise after the insertion of a specific coin in a slot provided for that purpose, the turning being effected by a motor, which is not shown. On the

35 shaft B there is mounted a disc C, provided with two curved grooves c^1 and c^2 . A bolt d^1 engages in the groove c^1 , the said bolt being fixed to a bar D, pivoting about a fixed pin a^1 . The groove c^1 is so designed that

40 when the disc C is in the angular position shown on Fig. 1 a rotation of the shaft B clockwise causes the bar D first to pivot in the opposite direction until the highest point of the bolt d^1 is reached and afterwards

45 to return to its original position. On the free end of the bar D a connecting rod E is joined to which one end of a two-armed lever F is connected by pin joint. The two-armed lever F is pivotally mounted on a

50 fixed pin a^2 . The other end of the lever F is shaped as a fork f^1 and embraces a bolt g^1 which is mounted on a spindle G carrying a stop collar g^2 . The spindle G is guided in a tube H slideable in a stationary cylin-

der a^3 and carrying on its lower end the 55 tear-off punch h^1 . In the path of the tear-off punch h^1 lies the end, shaped like a hook i^2 of a clamp i^1 , which is mounted on a stirrup J so that it can rotate about an axis lying in the plane of the drawing and is controlled by the gripper (not shown). The stirrup J can slide on a fixed rod a^4 against the action of a spring i^3 . A little way above the hook i^2 a strip of stamps a^5 ends, being coiled up on a rotatable stamp roll a^6 . 60

The stamp-strip a^5 can be seized by a two-part gripper 7, 8, and be drawn into the path of the tear-off punch h^1 . The two parts of the gripper 7, 8, are mounted on 65

the free ends of two levers 12, which swing 70 on two co-axial pins and are acted upon by two springs 11. The gripper is also connected as will now be described with the lever F.

On one end of the bolt g^1 , engaged by the fork f^1 , (Fig. 1), is mounted a downwardly directed controlling rod 2, (Fig. 5), which carries a roller 1 on its lower end. By means of said roller, rod 2 bears on one arm 75

of an oscillatory two-armed lever 3, acted upon by a spring 21 and provided with a 80 nose 24. The other arm of the lever 3 is provided with a set-screw 5, which bears against a lug of a two-armed lever 6, also pivotally mounted and connected to lever 3

by a spring 4, the ends of which engage the 85 arm of lever 3, carrying set-screw 5 and one arm of lever 6. In the free end of the other arm of lever 6 is mounted a bolt 17, which is provided with a recess 23, of the shape

shown particularly in Fig. 6. To the bolt 17 90 are pivoted two links 9, the free ends of which are pivoted to the two parts of the gripper 7, 8. On the pivot pin of the gripper is also mounted to swing a latch member

15, in which is cut a groove 22, of the shape 95 shown in the drawing, to receive the bolt 17, and which is connected to said bolt by a spring 16. The groove 22 is provided with a nose 25. On the frame A are also mounted

two fixed abutments 13 and 19, and a roller 20, which co-acts with the latch member 15 and the action of which will be later 100 described. Below the stamp strip a^5 a

water pot a^7 is provided being shut off by a stopper a^8 which sucks up the moisture. Against the stopper a^8 there lies a wetting roller k^2 which is rotarily mounted on one end of a two-arm lever k^1 . The 105

lever h^1 is rotarily mounted on a cranked two-arm lever K pivoting under friction around a fixed pin a^9 and lies with its free end on a pin h^3 under the action of a spring 5 (not shown), the said pin h^3 being mounted on the lever K. One arm, h^4 , of the lever K projects into the path of two pins g^4 and g^5 which are mounted on a connecting rod G^3 fixed to the bolt g^1 . The lower pin g^4 , in 10 the position shown in Fig. 1 of the different parts rests below against the arm h^4 . The upper pin g^5 is distant from the lower one by an amount which is equal to the distance of the stop collar g^2 from the front face of 15 the tube H, increased by the distance of the lower bounding surface of the tear-off punch h^1 from the moistening roller h^2 . To the arm h^5 of the lever K a bolt h^6 is provided which engages in a groove m^1 of a guide rod 20 M. The latter is pinjointed to one arm of a two-arm lever N^1 , which is mounted on a shaft N mounted in the casing A. On this shaft a comb-shaped feeler N^2 is also mounted. To the second arm of the lever N^1 25 a tierod P is pinjointed, the other end of which is jointed to a lever Q. This latter is pivotally mounted on the pin a^1 . Besides this there is mounted pivotally on the pin a^1 a two-arm lever R against the one arm 30 of which, connected with the lever Q by a spring q^1 , a shoulder q^2 of the lever Q lies. The other arm of the lever R carries a bolt r^1 which engages in the curved groove c^2 35 on the disc C. The groove c^2 is so designed that in the angular position of the disc C, shown in Fig. 1, a rotation of the disc C clockwise causes the lever R to pivot in the opposite direction up to the highest position of the bolt r^1 and afterwards to 40 return to its original position. Finally on the pin a^1 a toothed segment T is pivotally mounted. This toothed segment T carries a pin t^1 which projects into the path of the lever Q and is distant from the latter by a given amount in the position of the 45 parts shown by Fig. 1. The toothed segment T lies, under the action of a spring t^2 , against a fixed pin a^{10} . It meshes with a pinion V which is coupled with a second 50 toothed segment V^1 . The latter meshes with a rack w^1 provided on a slideable table W. The edge of the table W which is on the left side of the drawing lies opposite the feeler N^2 and, like the latter, is of comb design in 55 suchwise that the feeler N^2 can swing through without hindrance (Fig. 3). On to the table W anything to be posted, as for instance a letter W², can be passed from outside through a slot which is in the front wall 60 (cut away) in such a manner that it covers the comb slots in the table. Below the table W is a funnel a^{11} lying opposite to the tear-off punch h^1 .

If it is required to take from the above device an unmoistened stamp, a coin corre-

sponding to the value of the stamp is merely put into the slot provided. The shaft B and with it the disc C then rotate clockwise and, through the agency of the lever D, the connecting rod E and the lever F, a lowering of the spindle G takes place, together with the connecting rod G^3 and connecting rod 2. As soon as the collar g^2 strikes on top of the tube H the latter is carried along in the movement and the tear-off punch h^1 75 approaches the stamp, which has meantime been pulled forward by the gripper 7, 8. The forward feed of the stamp strip is accomplished as follows: The lowering of the rod 2 has swung the lever 3 in anti-clockwise direction against the pressure of spring 21, by means of the roller 1. In this angular movement of lever 3, lever 6, connected therewith by spring 4, takes part, so that it also turns about its axis in anti-clockwise 80 direction. In the beginning of the swinging movement of lever 6, pin 17 moves through the narrower part of groove 22 of latch member 15, and the gripper 7, 8, is accordingly closed by the links 9, and takes hold 85 of the stamp-strip a^5 , whereupon the levers 12 take part in the movement of the lever 6 against the pressure of the springs 11. When, in this movement, the lever 6 strikes against the lug 13, the stamp-strip has been drawn 90 out for the length of one stamp. After the engagement of lever 6 against lug 13, lever 3 turns alone in anti-clockwise direction and engages by its lug 24 against one of the levers 12 and turns it in the same direction. 95 The other lever 12 takes part in this movement and therefore the gripper 7, 8, opens again and releases the stamp-strip. During the opening of the gripper, the latch member 15 moves in the direction of the arrow x , relatively to the pin 17, held stationary by the lug 13, until the nose 25 has moved out of the recess 23 of the pin 17. As soon as this has taken place, said member 15 moves into the latching position shown in Fig. 6, under 100 the influence of spring 16, in which said member is prevented from moving in the opposite direction to the arrow x , whereby the gripper 7, 8, is prevented from closing too soon. When, in the further operation, 105 the rod 2 is again raised, all the parts, controlling the gripper 7, 8, return to their original positions shown in Fig. 4, under the influence of the springs 21, 11 and 4, and the roller 20, in which positions the levers 12 110 bear on the lugs 19 and the gripper 7, 8, is ready to again seize the end of the stamp-strip a^5 . During these movements, owing to the guiding of the bolt r^1 in the groove c^2 115 the lever R has been rotated anticlockwise. Under the action of the spring q^1 the lever Q follows the rotation and transmits the latter, but in the opposite direction, through the draw-rod P to the lever N^1 and consequently to the feeler N^2 . The latter 120

125

130

pivots through the comb-slots in the table W. On the rotation of the lever N¹ the guide rod M slides, and after a short shift the left stop face of the slot m¹ comes to lie 5 against the bolt k⁶. The lever K is now rotated anticlockhandwise so that the moistening roller k² moves out of the path of the tear-off punch h¹. The ratios of gearing are so contrived that this takes place before the 10 tear-off punch has torn a stamp off. Before this latter takes place meanwhile the table W has also been shifted to the right into the position shown by Fig. 2. This is brought about by the fact that in its rotation the lever Q comes to lie against the pin t¹ and thereupon carries along with it the toothed 15 segment T. The rotation of the latter brings about, through the agency of the pinion V, the toothed segment V¹ and the rack w¹, a 20 shifting movement of the table W to the right. After the tearing off of the stamp the clamp i¹ swings out and releases the stamp so that the latter falls into the funnel a¹¹ and can be taken out (Fig. 2). On further 25 rotation of the disc C the individual parts return again to their original position, namely, the toothed segment T and through it the table W, owing to the action of the spring t² and the stirrup J under the action of the 30 spring i³.

If the thing to be posted, for instance the letter W², is to be provided with a stamp, the letter is thrust through the slot provided for that purpose onto the table W in such a way 35 that it overlies its comb-slots. After the coin has been inserted there take place in the first instance the same movements as when taking out an unwetted stamp. But the feeler N² is now unable to swing through the 40 comb-slots of the table W because it strikes against the letter W². From the moment of its so striking (dotted line position on Fig. 1) the feeler N² and also the parts connected with it N¹, M, P, Q, remain at rest, while the 45 lever R swings onwards under the action of the spring q¹. The arrangement is such, however, that the feeler N² strikes against the letter W² shortly before the lever Q would come to lie against the pin t¹ and the 50 left stop face of the slot m¹ against the bolt k⁶. Consequently the table W also remains at rest and the lever K is not influenced by the feeler N². On the descent of the tear-off punch h¹, finally the pin g⁵ comes to lie 55 against the arm k⁴ of the lever K. According to what has been explained above this takes place when the stamp held between the hook i² of the clamp i¹ and the tear-off punch h¹, and which has already been detached 60 from the stamp strip a⁵, comes to lie against the moistening roller k². On further descent of the tear-off punch h¹ the lever K is rotated anticlockhandwise by the pin g⁵, the pin k⁶ sliding in the groove m¹. In the rotation of 65 the lever K the moistening roller k² passes

under the stamp and wets it. The moistening roller k² finally passes out of the path of the tear-off punch h¹ when it approaches the letter W². Shortly before the tear-off punch h¹ impinges on the letter W² the clamp i¹ 70 swings out and releases the stamp which is now firmly pressed by the tear-off punch h¹ on to the letter. Hereupon the several parts go back into their original position and the letter can again be taken out of the machine 75 provided with the desired stamp.

Claims:

1. In a stamp delivery machine, a driving element, a moistener, two systems of connections interposed between said driving element and said moistener whereby when a letter to be posted has been introduced one of said systems will move said moistener over the adhesive surface of the stamp while the other system keeps said moistener out of the 85 path of the stamp to be issued when a letter is not inserted.

2. In a stamp delivery machine, a stamp supply, a tear-off punch, a letter support, a feeler cooperating with said letter support, a moistener in the path of said tear-off punch and means connecting said feeler to said moistener whereby when no letter is to be stamped said moistener is shifted out of the path of the tear-off punch. 95

3. In a stamp delivery machine a stamp-strip supply, a tear-off punch, a letter support disposed beneath said punch, one end of said support being bifurcated, a comb-shaped feeler disposed adjacent to and co-operating with said letter support, a moistener in the path of said tear-off punch and means whereby when said feeler is permitted to swing past said letter support an operative connection is established between said feeler 100 and said moistener, to shift said moistener out of the path of said tear-off punch.

4. In a stamp delivery machine a stamp-strip supply, a tear-off punch, a letter support, a feeler cooperating with said letter support and means connecting said feeler to said letter support whereby when said feeler swings through said letter support it is shifted out of the path of the tear-off punch. 110

5. In a stamp delivery machine a stamp-strip supply, a tear-off punch, a shiftable letter support, a feeler associated with said letter support, an arm positively connected to said feeler for operating the same, a member positively connected to said letter support for shifting the same, a driving element and arm positively connected thereto, a second arm interposed between the feeler arm and said driving arm and resiliently connected to said driving arm and a pin projecting 115 from said letter support shifting member into the path of said second arm, substantially as and for the purpose described. 120

6. In a stamp delivery machine of the class described a stamp-strip supply, a tear-off 130

5 punch for detaching stamps, a feeler, a driving element provided with a pair of cam grooves, means controlled by one of said cam grooves and positively connected to said tear-off punch for controlling the same and means controlled by the other of said cam grooves and resiliently connected to said feeler for controlling the same.

7. In a stamp delivery machine a stamp supply, a tear-off punch for engaging said stamps, a letter support disposed beneath said tear-off punch, one end of said letter support being formed with comb slots, a comb-shaped feeler disposed adjacent this 15 end of the letter support, a driving element, a moistener and a system of operating means whereby when said feeler is permitted to swing past said letter support, said letter

support will be shifted and said moisture moved to inoperative position.

8. In a stamp delivery machine a stamp strip supply, a tear-off punch for engaging said stamps, a letter support disposed beneath said punch, a feeler associated therewith, a moistener and means whereby the presence of a letter on said support causes said moistener to move over the adhesive surface of the stamp and said letter support to remain in a position beneath said punch.

25 The foregoing specification signed at Es- 30
sen, Germany, this 26th day of July, 1920.

HERMANN THUN.
